UNITED STATES PATENT OFFICE.

CHARLES GREEN, OF READFIELD, MAINE.

CLUTCH-HOOK.

SPECIFICATION forming part of Letters Patent No. 274,935, dated April 3, 1883.

Application filed February 14, 1883. (No model.)

To all whom it may concern:

Be it known that I, CHARLES GREEN, of Readfield, in the county of Kennebec, State of Maine, have invented a certain new and useful Improvement in Clutch-Hooks, of which the following is a description sufficiently full, clear, and exact to enable any person skilled in the art or science to which said invention appertains to make and use the same, reference being had to the accompanying drawings, forming a part of this specification, in which—

Figure 1 is a side elevation of my improved hook detached from the rope; Fig. 2, an edge view of the same; and Fig. 3, an isometrical perspective view, representing the hook in use.

Like letters of reference indicate corresponding parts in the different figures of the drawings.

20 My invention relates to that class of clutch-hooks which are employed in connection with tackle for raising heavy weights, moving buildings, &c.; and it consists in a novel construction and arrangement of the parts, as hereininafter more fully set forth and claimed, by which a simpler, cheaper, and more effective device of this character is produced than is now in ordinary use.

30 The nature and operation of the improvement will be readily understood by all conversant with such matters from the following explanation, the extreme simplicity of the invention rendering an elaborate description unnecessary.

35 In the drawings, A represents the body of the hook, and B the clevis or link, which is U-shaped in form and detachably secured to the hook by means of the bolt C and spring pin or key D. The upper end of the hook is elongated, as shown at E, and curved outwardly, its convex edge, or that portion nearest the point a, being serrated, or provided with angular indentations, as shown at x.

In the use of my improvement the hook A is 45 attached to the weight or article to be raised,

as shown in Fig. 3, the end of the rope G being passed through the link B from the side next the point a of the hook, and drawn as far as possible, or until the body of the rope is taut. A strain is then brought to bear on the 50 rope, raising the link B and causing the rope to be clutched and securely held between the link and serrated portion x of the hook in a manner which will be readily obvious without a more explicit description.

55 In order to better understand the principle on which the hook operates, it will be seen that when the weight H is raised, by drawing up the rope G, and suspended, as shown in Fig. 3, the vertical axial line of the rope, if 60 extended, will touch the center of gravity in the weight, and that the bolt C stands outside of said line, thereby causing the rope to be clamped between the link and serrated end of the hook.

65 In all positions where it is necessary to advance the hook on the rope to take a new bite or hold of the same, it will be obvious that it may be readily accomplished by slipping the link along the rope to any desired position, thus making a great saving in time over the usual method of shortening or taking up the draft end of the rope through the tackle-block, especially in moving buildings and work of a similar character.

70 It will also be obvious that when the end of the rope cannot be conveniently passed through the link B the link may be readily detached from the hook, passed over the rope, and attached again by means of the pin D.

80 Having thus explained my invention, what I claim is—

The hook A, having the serrated end E, and provided with the link B and bolt C, combined and arranged to operate substantially as set forth.

CHARLES GREEN.
